[57] **CLAIM**

The ornamental design for a collapsible trailer boat, as shown and described.

DESCRIPTION

FIG. 1 is a longitudinal side view of a collapsible trailer boat embodying our new design, including a tent shown in phantom lines for illustrative purposes only;

FIG. 2 is a front view without the tent;

FIG. 3 is an overall bottom plan view of the boat shown in FIGS. 1 and 2;

FIG. 4 is a side view of the collapsible trailer boat showing a modified form thereof;

FIG. 5 is the same, a front view;

FIG. 6 is the same, a rear view;

FIG. 7 is a side view of the forward part of the collapsible trailer boat;

FIG. 8 is a top view of the fore part;

FIG. 9 is a front view of the fore part; and

FIG. 10 is a rear view of the fore part.
